FOLDABLE STOOL

Max Krischer, Brooklyn, N. Y., assignor to
Krischer Trading Corporation, Brooklyn, N. Y.

Application December 31, 1936, Serial No. 118,555

3 Claims. (Cl. 155—149)

This invention relates to new and useful improvements in a foldable stool.

The invention has for an object the construction of a stool which is characterized by a member having upper and lower hinge sockets and U-shaped frames associated with said sockets in a novel manner.

Still further the invention proposes the provision of a pair of top inverted U-shaped frames having the ends of their arms hingedly engaging said lower hinge sockets, and also provided with a flexible seat connected between the parallel portions of said frames.

Still further the invention proposes the provision of a pair of bottom U-shaped frames having their ends hingedly engaging said upper hinge sockets to form legs for the stool and associated with certain braces for holding the stool in an open position.

Still further the invention proposes the provision of an arrangement which permits the relative adjustment of the upper and lower sockets and adjustment of the braces so that the height of the stool may be varied and the tension at which the flexible seat is normally disposed may also be changed.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:—

Fig. 1 is a perspective view of a foldable stool constructed according to this invention.

Fig. 2 illustrates a bottom perspective view of the stool shown in Fig. 1 partially closed.

Fig. 3 is a perspective view of the stool entirely closed.

Fig. 4 is a bottom elevational view of Fig. 1.

Fig. 5 is a fragmentary enlarged sectional view taken on the line 5—5 of Fig. 1.

Fig. 6 is an end elevational view of a stool constructed according to a modification of this invention.

Fig. 7 is a side elevational view of Fig. 6.

Fig. 8 is a fragmentary sectional view taken on the line 8—8 of Fig. 7.

Fig. 9 is a perspective view of a portion of Fig. 8.

Fig. 10 is a view similar to Fig. 8 but illustrating another modification of the invention.

The foldable stool, according to this invention, comprises a member 10 having upper sockets 11 and lower sockets 12. A pair of top inverted U-

shaped frames 13 are arranged to have the ends of their side arms hingedly engaging in the lower hinged sockets 12. A flexible seat 14 is mounted between the central portions of the frames 13. A pair of U-shaped arms 15 have the ends of their arms hingedly engaging in the upper hinged sockets 11. A releasable brace 16 is arranged between the central portions of the bottom frames 15. Foldable braces 17 are mounted between the central portions of the upper and lower frames.

The member 10 comprises a pair of adjacent sheets of material riveted or welded, or in any other manner secured together, face against face, and having their edge portions turned into tubular portions forming the hinge sockets. Holding brace irons 20 are connected between the side arms of the inverted U-shaped frames and serve to hold the side arms in positions to prevent the disengagement of the end portions of the side arms from the hinge sockets. The flexible seat 14 is attached to the central portions of the frames 13 by reason of having the end portions 14^a bent over portions of the frame and secured by lines of stitches 21. The bottom frames 15 have offset portions 15^a at the centers which form sockets for the braces 16 and 17.

The brace 16 comprises merely a rod which has one end 16^a permanently bent over the offset portion 15^a and has its other end formed into a hook 16^b which is adapted to be hooked on to the offset portion 15^a of the other frame 15. Each of the foldable braces 17 comprises a pair of brace sections 17^a and 17^b pivotally connected at their inner ends by inter-engaging loop portions and at their outer ends provided with hook portions 17^c which permanently engage portions of the top and bottom frames. The top hook 17^c is held against lateral sliding by the fact that it engages through the flexible seat 14. The bottom hooks 17^c are held against shifting by reason that they engage the offset portions 15^a.

The stool is shown in its open position in Fig. 1. The brace 16 prevents the leg frames 15 from spreading outwards. The side braces 17 prevent the top frames 13 from moving together when one sits on the flexible seat 14. The flexible seat itself prevents the top frames from spreading apart. Thus a sturdy and rigid stool is produced.

To fold the stool it is first necessary that the brace 16 be unhooked at its releasable end. Then the bottom frames 15 are folded upwards into and between the top frames 13. The bottom frames are slightly narrower so that they may fit within the top frames. The side braces 17

during this folding operation double upon themselves, as clearly shown in Figs. 2 and 3. The top frames 13 are then folded together. In Fig. 2 the stool is shown partially folded, while in Fig. 3 it is completely folded.

In Figs. 6-9 inclusive, a modified form of the invention has been disclosed in which provision is made for adjusting the height of the stool and for adjusting the tension of the flexible seat. In 10 this form of the invention there is a member 10' which has separate sections, one of these sections being provided with the bottom sockets 12' and the other with the top sockets 11'. These sections comprise adjacent strips of material having 15 aligned vertical slots 25 through which clamp screws 26 pass. It is possible to loosen the clamp screws and then shift the sections relative to each other so as to space apart or move together the top and bottom sockets 11' and 12' respectively.

The top sockets are formed by coiling edge portions of one of the sections, in opposite directions, that is, a small portion of the edge portion is coiled in one direction, then the next adjacent portion coiled in the other direction, and the following section back into the first direction, etc. This is clearly shown in Fig. 9. The lower sockets 12' are similarly constructed. The finished sockets comprise small spaced tubular portions.

A pair of top inverted U-shaped frames 13 have the ends of their arms hingedly engaging the lower sockets 12'. A flexible sheet 14 is mounted between the central portions of the said frames 13. A pair of bottom U-shaped frames 15 have the ends of their arms hingedly engaging the upper sockets 11'. There is a releasable brace 16 mounted between the central portions of the said bottom frames.

There are also foldable side braces 17' formed of adjacent sections 17^{aa} and 17^{bb} hingedly connected together. These braces are connected between the central portions of the upper and lower frames. Each of the sections 17^{bb} of these braces is formed from end aligned sections 27^{bb} connected together with a coupling 28. The coupling 28 comprises a tubular member, the ends of which are formed with right and left hand threads which engage right and left hand threads on the adjacent ends of the sections 27^{bb}. It is possible to turn the coupling 28 to lengthen or reduce the length of the brace sections 17^{bb}.

The sockets 11' and 12' may be relatively adjusted to change the height of the stool and furthermore to change the normal stretched position of the flexible sheet 14. Furthermore, the brace sections 17^{bb} may be extended or retracted to partially or fully compensate for the change of location of the sockets 11' and 12' so as to make the flexible seat 14 completely taut or slack to any desired degree.

In Fig. 10 another modified form of member 10' has been illustrated which is formed from a single strip of material having portions 11'' from the top edge bent alternately in opposite directions and having other portions 12'' from the bottom edge bent alternately in opposite directions. These bent portions are of sufficient length to extend to the center of the member 10'' and are there fixedly secured by rivets 30. These bent

portions form upper and lower sockets similar to the corresponding sockets, and for the same purposes, as previously mentioned.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:—

1. A foldable stool, comprising a member having upper and lower hinge sockets, a pair of top inverted U-shaped frames having the ends of their arms hingedly engaging said lower hinge sockets, a flexible sheet between the central portions of said frames, a pair of bottom U-shaped frames having the ends of their arms hingedly engaging said upper hinge sockets, a releasable brace between the central portions of said bottom frames, and foldable braces between the central portions of said upper and lower frames, and brace irons engaged between the side arms of said inverted frames to hold the ends of said frames in said sockets.

2. A foldable stool, comprising a member having separate sections formed with upper and lower hinge sockets, a pair of top inverted U-shaped frames having the ends of their arms hingedly engaging said lower hinge sockets, a flexible sheet between the central portion of said frames forming the seat portion of said device, a pair of bottom U-shaped frames having the ends of their arms hingedly engaging said upper hinge sockets, a releasable brace between the central portions of said bottom frames, foldable braces between the central portions of said upper and lower frames to prevent said top frames from collapsing when one sits thereon, and means for adjustably connecting together the sections of said member so that said upper hinge sockets may be moved from said lower hinge sockets to adjust the slack of said flexible seat.

3. A foldable stool, comprising a member having separate sections formed with upper and lower hinge sockets, a pair of top inverted U-shaped frames having the ends of their arms hingedly engaging said lower hinge sockets, a flexible sheet between the central portion of said frames forming the seat portion of said device, a pair of bottom U-shaped frames having the ends of their arms hingedly engaging said upper hinge sockets, a releasable brace between the central portions of said bottom frames, foldable braces between the central portions of said upper and lower frames to prevent said top frames from collapsing when one sits thereon, and means for adjustably connecting together the sections of said member so that said upper hinge sockets may be moved from said lower hinge sockets to adjust the slack of said flexible seat.

4. A foldable stool, comprising a member having separate sections formed with upper and lower hinge sockets, a pair of top inverted U-shaped frames having the ends of their arms hingedly engaging said lower hinge sockets, a flexible sheet between the central portion of said frames forming the seat portion of said device, a pair of bottom U-shaped frames having the ends of their arms hingedly engaging said upper hinge sockets, a releasable brace between the central portions of said bottom frames, foldable braces between the central portions of said upper and lower frames to prevent said top frames from collapsing when one sits thereon, and means for adjustably connecting together the sections of said member so that said upper hinge sockets may be moved from said lower hinge sockets to adjust the slack of said flexible seat, a second means on said foldable braces for adjustably connecting together portions thereof so that said braces may be adjusted to compensate for the adjustment to said member to change the height of said stool.

MAX KRISCHER.
